UNITED STATES PATENT OFFICE.

NAOMI E. NICHOLSON, OF LOS ANGELES, CALIFORNIA.

TWINE-CUTTER.

1,169,052.

Specification of Letters Patent.

Patented Jan. 18, 1916.

Application filed November 30, 1914. Serial No. 874,587.

To all whom it may concern:

Be it known that I, NAOMI E. NICHOLSON, a citizen of the United States, residing at Los Angeles, in the county of Los Angeles, State of California, have invented new and useful Improvements in Twine-Cutters, of which the following is a specification.

This invention relates to a twine cutter.

It is the object of this invention to provide a device for cutting twine and which is particularly adapted for use by package wrappers in severing the twine after tying same on the package, and which is used in lieu of shears or like implements.

Another object is to provide a tool for cutting twine having a demountable cutting blade formed with a V-shaped cutting edge, in which the blade can be readily removed and replaced when it is desired to renew or resharpen same.

A further object is to provide a holder for a twine-cutting blade which can be readily grasped in the hand, together with the cord or twine to be cut and the latter severed on a drawing or pulling movement of the tool in opposition to the secured end of the cord.

Another object is to provide a twine cutter comprising a demountable cutting blade and holder therefor which is durable and which can be economically manufactured and sold at small cost.

The invention is illustrated in the accompanying drawings, in which:

Figure 1 is a perspective view illustrating the application of the invention. Fig. 2 is a view of the device in side elevation, with parts broken away. Fig. 3 is a view in end elevation, as seen in the direction indicated by the arrow 3 in Fig. 2. Fig. 4 is an enlarged end view of the device, as seen in the direction indicated by the arrow 4 in Fig. 2, with parts broken away. Fig. 5 is a perspective view of the demountable cutting blade. Fig. 6 is a view in perspective illustrating a modified form of the invention, showing it as adapted to be readily mounted on a counter or other support.

More specifically, 10 indicates the body portion of the device which, in the form shown in Figs. 1 to 4 inclusive, comprises a blade holder adapted to be held in the hand and grasped between the thumb and first and second fingers. The body member or blade holder 10 is preferably formed of cast metal or other material and consists of a

ring portion 11, having an open portion substantially of piriform formation to receive the second or middle finger and which is of sufficient size that the finger may extend diagonally therethrough to engage the ring 11 between the second and third joints of the finger, as particularly shown in Fig. 1.

1. The outer face of the ring 11 converges on one side thereof into an extended portion 12, which portion is formed with a substantially flat face 13, to form a seat for the thumb and against which a cord or twine 14 to be cut is held by the thumb, as shown in Fig. 1.

Formed on the extension 12 opposite the flat face 13, is an outwardly extending ear 15, having a concave face forming a seat 16, for the end of the first finger. The extension 12 is formed with a projecting portion 17, extending rearwardly of the ring 11, that is, on the side of the latter disposed toward the palm of the hand when the body member 10 is grasped in the fingers. Formed on this projecting portion 17 is an 80 outwardly extending portion 18, arranged at right angles to the face 13, on which is formed a rigid jaw member 19.

The jaw member 19 extends substantially parallel with the face 14 and is spaced 85 therefrom to form an open ended twine receiving slot 20, the walls of which converge inwardly and are formed by the inner face of the jaw member 19 and the face 13 at the outer edge of the extension 12; the outer 90 edge of the extension 12 forming a rigid jaw member 21, coöperating with the jaw member 19 to form the slot 20.

Formed in the extension 12, projection 18 and the jaw member 19, is an open ended slot 95 22, disposed at right angles to the slot 20 and terminating approximately midway of the length of the jaw members 19 and 21 to form shoulders 23 and 24. This slot 22 is designed to receive a demountable cutting 100 blade 24, having a V-shaped notch 25 on one end thereof, which notch is beveled to form a convergent or V-shaped cutting edge. The blade 24, when inserted in the slot 22, extends across the slot 20, with the end of the 105 blade carrying the V-shaped cutting edge 25 abutting against the shoulders 23 and 24, with the V-shaped cutting edge 25 disposed across the twine receiving slot 20 and opening to the slot 20 in such manner that when 110 a cord 14 is introduced into the latter, it will be engaged by the cutting edge 25, as shown

in Fig. 4. The upper wall of the blade receiving slot 22 thus forms a tongue 26, adapted to project over the cutting blade 24. This tongue 26 is formed with an aperture 27 adjacent its outer end, adapted to register with a corresponding aperture 28 formed in the cutting blade 24. The projection 18 is formed with a threaded bore 29, arranged opposite the aperture 27, which is adapted 10 to receive the threaded stud of a screw 30, which screw is adapted to be inserted through the apertures 27 and 28 and screwed into the bore 29 to clamp the blade 24 between the tongue 26 and the bottom wall of 15 the blade receiving slot 22. The screw 30 thus serves to removably hold the cutting blade 24 in position on the blade holding member 10. The blade holder 10 is fitted 20 with an eye 31, adapted to receive a looped cord or ribbon 32, by means of which the device may be suspended from any suitable support.

In the application and operation of the invention as previously described, the device is 25 grasped in the hand with the second finger passing diagonally through the ring 11 and engaged between the second and third joints of this finger, with the thumb seated on the face 13 and the outer end of the finger engaging the seat 16. The cord 14 to be cut 30 is introduced into the open ended slot 20 and engaged by the V-shaped cutting edge 25 of the blade 24 by hooking the jaw members 19 and 21 around the cord, as illustrated in 35 Fig. 1, with the fastened end 33 of the cord extending below the extension 12 and the free end 34 of the cord extending across the flat face 13, where it is engaged by the

thumb. A pull being exerted on the device in the direction indicated by the arrow in 40 Fig. 1, the cutting edge 25 of the blade will engage the cord 14 and sever same.

In the modified form of the invention illustrated in Fig. 6, it is shown as adapted to be permanently mounted on a counter, table or 45 the like. In this form of the invention the blade supporting member 10 is formed with a flange 35 adapted to sit on a suitable supporting surface 36 and secured to the latter by means of a screw 37 or any other suitable 50 fastening means. The cord 14 to be severed is introduced into the open ended slot 20 and drawn into cutting engagement with the V-shaped cutting edge 25 of the blade 24.

What I claim is:

A twine cutter, comprising a loop member of elongate form provided with an off-set ear on one side for engagement by a finger and an off-set jaw member oppositely disposed to said ear at one end thereof, said body member comprising a pair of spaced jaws having registering grooves formed therein lying in a plane substantially parallel to the plane of the jaws and open at the closed end of the jaw member, a cutting plate disposed in said grooves, and a set screw mounted on the member for detachably securing the knife in place.

In witness that I claim the foregoing I have hereunto subscribed my name this 9th day of November, 1914.

NAOMI E. NICHOLSON.
